UNITED STATES PATENT OFFICE.

GILBERT W. ALLEN, OF CHERRY CREEK, NEW YORK.

THERMOSTATICALLY-OPERATED BURNER FOR LAMPS FOR HEATING INCUBATORS.

1,239,859.

Specification of Letters Patent. Patented Sept. 11, 1917.

Application filed December 23, 1916. Serial No. 138,601.

To all whom it may concern:

Be it known that I, GILBERT W. ALLEN, a citizen of the United States, residing at Cherry Creek, in the county of Chautauqua and State of New York, have invented certain new and useful Improvements in Thermostatically-Operated Burners for Lamps for Heating Incubators; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in heating apparatus for incubators and especially in the provision of a thermostatically-operated device whereby the intensity of the flame from the wick of an oil burner may be regulated without distorting the flame.

The invention consists more specifically in the provision of an elongated flattened tube having a vertical movement over the wick tube and serving to retain a perfect blaze at all times, equal to the effect produced by the raising and lowering of the wick by the usual turning screw.

The present invention comprises other detailed features, combinations and arrangements of parts which will be hereinafter fully described, shown in the accompanying drawings and then specifically defined in the appended claim.

My invention is illustrated in the accompanying drawings, in which:—

Figure 1 is a view showing a thermostatically-operated lever connected to the means for regulating the intensity of the flame of the burner.

Fig. 2 is an enlarged detail sectional view through the burner and movable flame regulating member mounted about the wick tube.

Fig. 3 is a side elevation.

Reference now being had to the details of the drawings by letter, A designates a thermostatically-operated element of the usual construction adapted, when acted upon by different degrees of temperature, to cause a tilting of the lever B to which it is attached. Said lever is adapted to be pivotally mounted upon the frame of an incubator. In the present instance, I have shown the application of my invention to an ordinary oil

lamp, designated by letter C, and provided with a wick D mounted in a wick tube E upon the burner F, the latter fitting the lamp with threaded connections as usual. In order to permit the font of the lamp to be filled without unscrewing the burner, a filling tube H is secured to the burner in the manner shown.

Mounted to have a vertical play about the wick tube is a flat tubular member K conforming to and of slightly larger area than the wick tube and which flat tubular member is secured at its lower end to a disk N of sufficient weight to cause the flat tubular member to normally rest at its lowest limit of movement, in which position the upper edge of the wick tube and said flat tubular member will be flush, thus allowing the flame from the wick within the tube to burn freely.

A lever, designated by letter R, is pivotally mounted upon the loop P upon the under side of the burner and has one arm positioned underneath said disk and its other end engages the lever B.

In operation, when the lever B is tilted incident to the expansion of the thermostatic element, a similar movement will be imparted to the lever pivoted upon the burner and causing the flat telescoping tube to be raised a slight distance for the purpose of reducing the intensity of the flame from the wick of the burner, the movement of said flat tube having the same effect as the lowering of the wick to reduce the size of the flame.

Heretofore, it has been attempted to regulate the intensity of the flame of a burner by thermostatically-operated mechanism by the employment of means which impinges upon the sides of the flame to constrict the same or otherwise changing the blaze but which has been found objectionable.

By the provision of a flat tubular telescoping member mounted as shown and described, I have found from experience that a perfect blaze will be maintained at all times. The intensity may be regulated to a nicety by the delicate thermostatically-operated movements imparted to the levers whereby the telescoping member may be raised and lowered.

What I claim to be new is:—

A thermostatically-operated device for heating incubators, etc., comprising a burner having a shell with a wick tube, said shell of

the burner having a flat portion about said tube which is provided with a slot, a lever pivoted at one side of its center to said shell underneath the same and having a bowed arm, the convexed edge of which is adapted to bear against the under surface of the flange of said wick tube at its longitudinal center, the free end of said bowed arm resting upon a horizontal portion of the burner 10 and the other arm of the lever projecting

beyond the circumference of the burner, a thermostatically-operated tilting member one end of which is adapted to engage the outer arm of said lever, as set forth.

In testimony whereof I hereunto affix my 15 signature in presence of two witnesses.

GILBERT W. ALLEN.
